UNITED STATES PATENT OFFICE

FRED A. CHAPMAN AND WILLIAM KOVVIS, OF HILLSBORO, WISCONSIN

INTERNAL-COMBUSTION-ENGINE HEATER

Application filed September 13, 1928. Serial No. 305,772.

The invention aims to facilitate the starting of a cold engine utilizing a volatile liquid fuel as the motive medium.

In accordance with the invention, a heater 5 of novel and peculiar structure is disposed in close proximity to the oil pan and is connected with the water cooling system of an internal combustion engine to warm both the oil and the water with the result that starting 10 of the engine when cold is greatly facilitated, which is a desideratum.

While the drawings illustrate a preferred embodiment of the invention, it is to be understood that in adapting the means to 15 meet specific needs and requirements, the design may be varied and such other changes in the minor details of construction may be resorted to within the scope of the invention as claimed, without departing from the 20 spirit thereof.

For a full understanding of the invention and the merits thereof reference is to be had to the following description and the drawings hereto attached, in which:

25 Figure 1 is a side view illustrative of an embodiment of the invention.

Figure 2 is an enlarged transverse sectional view.

Figure 3 is a vertical longitudinal section 30 view of the heater.

Corresponding and like parts are referred to in the following description and designated in the several views of the drawings by like reference characters.

35 The numeral 1 denotes an engine of the internal combustion type, 2 the oil pan or crank case, and 3 the radiator through which the water is circulated for cooling the engine when in action. These parts are of well known construction and arrangement and are illustrated to demonstrate the application of the invention, which resides in the heater and peculiar construction and arrangement thereof.

45 The heater is designated by the numeral 4

and is elongated and of semi-circular formation in cross section. The heater is hollow and the flat side is depressed as indicated at 5, to receive an element 6 which may be a heating unit of any type. The space 7 50 formed between the inner and the outer walls of the body is of semi-circular outline and the water forming the cooling medium of the engine is circulated therethrough. A pipe 8 connects the lower portion of the space 55 7 at one end with the lower part of the radiator 3. A pipe 9 connects the front of the space 7 at the opposite end with the water jacket of the engine whereby to warm the latter by supplying warm water to the cooling 60 system. The heater is disposed with its flat side against the oil pan or crank case 2 so as to heat the oil simultaneously with the heating of the water contained in the water jacket of the engine, as will be readily appreciated. 65

Suitable means are employed for securing the heater and, as shown, strap irons 10 are employed to retain the device in the located position.

The heating element 6 illustrated and 70 preferred is of the electric variety and comprises a coil about which a wire is wound and which offers resistance to the flow of an electric current whereby heat is generated in a manner well understood.

75 The numeral 11 denotes an electric cord which may lead from a source of current supply and which is adapted to be plugged into a socket 12 at one end of the heater and to which the terminals of the wire wound 80 about the coil of the heating unit are connected.

When it is required to warm a cold engine to make starting thereof easy an electric current is caused to flow through the wire of 85 the heating element and the heat thus generated warms the oil in the pan 2 and the water in the cooling system of the engine. In a comparatively short time the engine is sufficiently heated to render starting easy and, 90

at the same time, the oil is warmed so as to flow and enable the operating parts to move easily.

What is claimed is:

5 In an internal combustion engine, a heater comprising a hollow body of semi-circular formation in cross section and having an open-sided recess formed in its flat side, said flat side being engaged against the oil pan 10 of the engine whereby the recess is closed by said pan, a heating unit mounted in the recess, and means connecting the hollow body with the water jacket and radiator of the engine.

15 In testimony whereof we affix our signatures.

FRED A. CHAPMAN. [L.S.]
